UNITED STATES PATENT OFFICE.

JOSEPH K. SHARPE, JR., OF INDIANAPOLIS, INDIANA, ASSIGNOR TO THE PNEUMATIC ELEVATOR AND WEIGHER COMPANY, OF INDIANAPOLIS, INDIANA, A CORPORATION OF INDIANA.

CENTRIFUGAL ELEVATOR.

SPECIFICATION forming part of Letters Patent No. 755,401, dated March 22, 1904.

Application filed January 21, 1903. Renewed August 31, 1903. Serial No. 171,454. (No model.)

To all whom it may concern:

Be it known that I, JOSEPH K. SHARPE, Jr., a citizen of the United States, residing at Indianapolis, in the county of Marion and State 5 of Indiana, have invented certain new and useful Improvements in Centrifugal Elevators, of which the following is a specification.

My present invention relates to elevators adapted to be used in lifting grain and such 10 like materials, and is especially adapted for use with threshing-machines to receive the grain from the auger or shake spout, through which it emerges from such machine, and lift it to a point from which it can be suitably delivered into a weigher or directly in a tank, 15 wagon, or other receptacle, as may be desired.

The object of my invention is to perform this work in a simple and effective manner, and the various features of said invention will 20 be first fully described and then pointed out in the claims.

Referring to the accompanying drawings, which are made a part hereof, and on which similar reference characters indicate similar 25 parts, Figure 1 is a side elevation of a threshing-machine or separator equipped with one of my improved elevators; Fig. 2, a top or plan view showing the said elevator and the adjacent portions of the separator; Fig. 3, a 30 transverse vertical sectional view through the elevator boot or housing and immediately adjacent parts on a considerably-enlarged scale as seen when looking in the direction indicated by the arrows from dotted lines 3 3 in Figs. 1 and 4, and Fig. 4 a longitudinal vertical sectional view thereof as seen when looking in the direction indicated by the arrows from the dotted lines 4 4 in Figs. 2 and 3.

I have shown a complete separator 21, including also part of a wind-stacker, for the purpose of illustrating the relative position thereto of the elevator embodying my invention when the same is attached to the separator and ready for operation. It will of course, 40 however, be understood that my improved elevator may be used with other forms of separator without departing from my invention, the form shown being merely for purposes of

illustration. There are, however, certain advantages in using this invention where a wind-stacker is employed greater than where other stackers are employed, as will appear hereinafter, and I have chosen to illustrate so much of a wind-stacker as makes this clear and have illustrated so much of the particular form of 55 wind-stacker which I prefer as is necessary for the purpose. In this form of wind-stacker the stacker-fan is mounted on the shaft 23 and is driven by a belt 24 from the separator-cylinder shaft 25, and the blast from said fan is 60 delivered into the base or straw-chamber portion 26 of said stacker and drives the straw from said chamber into and through the straw-carrier trunk or duct, of which only a fragment 27 is shown. 65

The elevator comprises a housing 31, having an inlet in one side to admit the grain, a throwing-wheel 32, contained in said housing and having an opening in one side corresponding to said inlet, a duct, preferably composed 70 of two sections 33 and 34, and a suitable separating-head 35, and these (in use) are rigidly secured to the separator-frame by various supporting slings and braces 36, a bracket 37, and stays 38 and 39, as shown, these being varied 75 in size, form, and arrangement according to the separator to which the elevator is attached.

The throwing-wheel is similar in form, arrangement, and operation to that shown and described in the Schuman patent, No. 603,925, 80 dated May 10, 1898, and in construction to that illustrated in the Schuman patent, No. 641,045, January 9, 1900, or No. 646,877, dated April 3, 1900, and therefore need not be further described herein. 85

The bearing 41, in which the shaft 42 of said throwing-wheel is mounted, is the same as that which forms the subject-matter of the Williamson patent, No. 663,372, dated November 7, 1899. Said throwing-wheel is preferably driven by a belt 43, running to a pulley 44 on the shaft 42 from a pulley 45 on a counter-shaft 46, and said counter-shaft is driven, preferably, by a belt 47, running to a pulley 48 thereon from a pulley on the cylinder-shaft 90 25 of the separator. It will be seen that I am

enabled by this provision of a counter-shaft to vary the speed of the throwing-wheel 32 as may be desired by simply varying the sizes of the pulleys 45 and 48.

- 5 The duct, as above stated, consists of two duct-sections 33 and 34, the lower one of which extends within the other. This enables them to be adjusted in relation to each other so as to vary the length of the duct, and thus permit the elevator to be conveniently attached to different sizes and makes of separators. It likewise permits the separating-head to be adjusted to a higher or lower level, according to the work to be done. The lower duct-section 33 has a vent at 30 of similar character and purpose to that which forms the subject-matter of the Patent No. 619,844, granted to The Pneumatic Elevator and Weigher Company, February 21, 1899, upon my application and assignment.

15 The separating-head 35 forms the subject-matter of a companion application dated and filed concurrently herewith, and therefore will not be further described herein.

- 25 In operation the grain as it is threshed comes from the separator through the grain-delivery spout thereof, which is commonly either what is known as a "shake-spout" or an "auger-spout." In Fig. 3 I have shown a fragment 51 of an auger-spout containing an auger 52 of a usual form. An inlet-spout 53 runs from this grain-delivery spout into the eye of the housing 31 of the elevator and carries the grain to the center of the throwing-wheel 32, which 30 impels it by centrifugal force through the duct composed of the duct-sections 33 and 34 into the separating-head 35, from which any air which may be carried with the grain will escape through the top of said separating-head, (which is reticulated or perforated, being commonly composed of woven wire,) while the grain will fall to the bottom of said head and be delivered through its mouth either to the weigher-drum 61 or to any other spout or receptacle which may be provided. For the purpose of illustrating a complete machine I have shown a weigher similar to that forming the subject-matter of the Schuman patent, No. 650,593, and a bagger similar to that shown 45 in the Schuman patent, No. 623,109.

50 In my elevator there are no changes of direction in the duct-pipe, and the grain is consequently thrown directly from the housing to the separating-head, which takes less power than any arrangement wherein changes of direction are embodied.

- 55 The duct runs at an angle from the place where the grain is received up to a sufficient height to secure the desired delivery therefrom and also sufficiently to the rear so that the delivery point is behind the threshing-machine. In an arrangement like that illustrated herein where the grain is being bagged on the ground it can be taken to a wagon 60 standing on either side of the separator with-

out changing the position of the elevator or bagger. If the wagon is on the same side of the separator as the elevator, the sacks can be placed therein from where they sit, while in case the wagon is on the other side of the separator the operative merely has to step across behind the separator from one side to the other to deliver the sacks thereto. All devices in the nature of "cross-conveyers" are thus generally dispensed with.

75 Having thus fully described my said invention, what I claim as new, and desire to secure by Letters Patent, is—

1. The combination, with a threshing-machine, of a housing secured thereto opposite the grain-delivery spout and having a central opening in the side nearest the threshing-machine, a grain-throwing wheel mounted in said housing also having a central opening in its side nearest the threshing-machine adapted to receive the grain as it comes from said grain-delivery spout in through the housing-opening and to act as a centrifugal grain-impeiling device, a duct leading from the neck of said housing in an inclined direction to the desired point of discharge, a separating-head on the end of said pipe, and a discharge-outlet on the under side of said separating-head, whereby the grain is thrown in a direct line from the throwing-wheel to the point of separation and thence discharged in one direction while the air and dust are discharged in another direction.

2. The combination, in an elevator, of a housing, a throwing-wheel therein, a duct leading directly from the discharge-opening of the housing to the required point of delivery and provided with a vent on its outer or under side, said duct being composed of two sections adjustable one upon the other, and a separating-head connected to the outer end of said duct and adapted to discharge the grain in one direction and permit the air to escape in another direction, substantially as set forth.

3. The combination in an elevator, of a housing having a material-receiving opening on one side, a throwing-wheel having a corresponding opening registering therewith, a shaft to said throwing-wheel carried by a bearing on said housing on the other side, a counter-shaft arranged upon said housing, pulleys on said shafts, a belt running from a pulley on the counter-shaft, to a pulley on the throwing-wheel shaft and another belt running from another pulley on the counter-shaft to a pulley on a shaft on the separator, substantially as shown and described.

In witness whereof I have hereunto set my hand and seal, at Indianapolis, Indiana, this 13th day of January, A. D. 1903.

JOSEPH K. SHARPE, JR. [L. S.]
